UNITED STATES PATENT OFFICE.

CHARLES Q. HOLST, OF MEMPHIS, TENNESSEE.

DESIGN FOR A STOCK-BOOK SHEET.

SPECIFICATION forming part of Design No. 25,401, dated April 21, 1896.

Application filed March 17, 1896. Serial No. 583,631. Term of patent 14 years.

To all whom it may concern:

Be it known that I, CHARLES Q. HOLST, a citizen of the United States, residing at Memphis, Tennessee, have invented and produced 5 a new and original Design for a Stock-Book Sheet, of which the following is a specification.

In the accompanying drawing I have illustrated my design in a plan view.

The leading feature of my design consists 10 in horizontal and vertical lines forming two end panels and a larger central panel, the end panels being open on one side, and located in each panel is a portion of a head of a hog comprising the snout and eye and one ear, 15 the ear extending forward and overhanging the eye and snout. In the center panel I arrange a series of horizontal lines connected by brackets, as shown. These lines begin at the

left, extending in a horizontal plane. From the first lines a bracket extends and this embraces lines at the top and bottom thereof, while the lines from this bracket embrace two brackets and from the two brackets extend other horizontal lines, which in turn extend to four brackets, and these brackets include other lines. 20 25

I claim—

The design for a stock-book sheet herein shown and described.

In testimony whereof I affix my signature 30 in presence of two witnesses.

CHARLES Q. HOLST.
